UNITED STATES PATENT OFFICE.

DAVID ERTER, OF SPRINGFIELD, OHIO, ASSIGNOR OF ONE-HALF TO BERT M. KENT,
OF CLEVELAND, OHIO.

ATTACHMENT FOR ROAD ROLLERS.

1,404,380.

Specification of Letters Patent. Patented Jan. 24, 1922.

Application filed October 2, 1919, Serial No. 327,838. Renewed May 31, 1921. Serial No. 473,968.

To all whom it may concern:

Be it known that I, DAVID ERTER, a citizen of the United States, and residing at Springfield, Clark County, State of Ohio, have invented certain new and useful Improvements in Attachments for Road Rollers, of which the following is a specification.

This invention relates to a device which is designed to scarify or loosen up the surface of an old roadbed preparatory to resurfacing it. In the form shown it consists of an attachment adapted to be secured to a road roller, and may be secured to the water tank as illustrated in Figure 1 of the drawings. The device embodies a row of scarifier teeth which may be reversed in position to act properly when the road roller is moving forward, or when the road roller is moving backward, the row of teeth being inclined downwardly and forwardly for the forward movement, and downwardly and rearwardly for the backward movement. The device furthermore includes simple, efficient, and easily operated means for adjusting the scarifier teeth and for yieldingly pressing them down so as to engage the roadbed. The novel features will be apparent from the following description taken in connection with the drawings. In the drawings,

Fig. 1 is a side view of the device secured to the rear end of a road roller;

Fig. 2 is a side view partly in section of the lower part of the device, showing the teeth projecting forwardly for forward movement;

Fig. 3 is a rear view of the attachment itself; and

Fig. 4 is a cross section on the line 4—4 of Figure 3 looking down.

In the drawings 10 represents the rear end of a water tank of a road roller carried by the wheels 11, and my invention is shown as secured to the rear end of this tank. It will, of course, be understood that my device may be secured on any moving vehicle.

The device embodies a fixed frame 12 which may be secured by any suitable means, such as arms 13 and 14 to the road roller or other vehicle, but is preferably mounted at a slight angle to the vertical, extending downwardly and rearwardly from the top. This frame 12 has the side bars 15 and 16 which are channel shaped on their facing

sides so as to form trackways, as shown particularly in Figure 4. A sliding frame 17 has side bars 18, 19 which fit in and slide longitudinally in the grooves in the side bars 15 and 16, and it will be understood that the bars 18 and 19 are not so long as the grooves in which they fit. A steam cylinder 20 is secured in any suitable way to the cross bars 21 and 22 of the main fixed frame, as for instance, by the bolts 23. A piston works in the cylinder 20 and has the projecting piston rod 24 which is connected at its lower end to the sliding frame 17 by the pivot pin 25 passing through the members 26, 27. The cylinder and piston may be operated by steam or compressed air, and there is a four-way valve 28 above the cylinder for regulating and controlling the admission of the fluid under pressure to the ends of the cylinder to operate the piston, moving it up or down.

Secured to and forming a part of the sliding frame 17, there are side flanges 29, 30 projecting rearwardly from said frame at its sides near the bottom. Extending across the machine and mounted in bearings in said side flanges 29 and 30, there is a rotary shaft 31 which carries the scarifying teeth 32. The shaft 31 is formed with depressions at intervals transversely thereof of the same shape as half section of one of the teeth, as shown at 33. A removable plate 34 fits over the top on the other side, and is secured to the shaft 31 by bolts 35 which serve to clamp the teeth in place, but permits removal when desired. In this device there is a single row of teeth in line, all projecting from the same side of the shaft. Limiting rollers 37 are secured on the ends of the shaft 31 to regulate the depth of the scarifying action.

The shaft 31 has secured to it arms 38, 39 on the inside and closely adjacent to the flanges 29 and 30, and these arms are provided with openings at their ends to receive a fastening pin. It will be understood that they move over the inner faces of the flanges 29 and 30 when the shaft 31 is turned, and the flanges 29 and 30 are provided with openings 40 in an arc in line with the openings in the ends of the arms 38 and 39. A locking shaft or pin 41 passes through the openings 40 and the openings in the ends of the arms 38 and locks the shaft 31 in any ad-

justed position. It will, of course be understood that any number of adjustments may be provided which are deemed necessary, but in practice I prefer to operate the 5 teeth at an angle of about 30° to the vertical.

It is believed that the operation of the device will be apparent from the foregoing description. When it is desired to operate when the machine is moving forward, the 10 shaft 31 and teeth 32 are turned to an angle of about 30° to the vertical projecting forwardly, and when it is desired to operate when the machine is backing, as is often the case on hills, the shaft 31 and the teeth are 15 turned to an angle of about 30° projecting rearwardly. The change in the adjustment is very simple and easy, and it will be observed that the structure of the device is such that it will operate easily and certainly 20 in reciprocating the scarifier shaft and its teeth with less chance of getting out of order and with no chance of undue wear. The fluid pressure operating mechanism, of course, furnishes a yielding pressure downward 25 on the scarifying teeth.

Having thus described the invention what I claim as new and desire to secure by Letters Patent is:

1. A reversible scarifier for road rollers 30 comprising a supporting frame adapted to be secured to a road roller and carrying trackways extending from its upper portion downwardly, a sliding frame having parts fitting and movable along said trackways 35 and having rearwardly extending side flanges at its lower end, a shaft rotatively mounted in said flanges, scarifying teeth secured to said shaft and projecting therefrom on one side, arms secured to said shaft 40 and movable across the face of said flanges when turned, means for securing said arms to said flanges in various adjusted positions, to make said teeth project either forward or backward at an angle to operate either 45 on a forward movement or a rearward movement, and means for yieldingly passing said sliding frame downwardly to make said teeth engage the road bed.

2. A scarifier for road rollers comprising 50 a supporting frame adapted to be secured to a road roller and having facing groove-like trackways facing each other at the sides extending downwardly and rearwardly at an angle, a sliding frame having side bearing portions travelling in said trackways, fluid pressure mechanism secured to said supporting frame at the central top portion above said sliding frame and provided with a piston rod connected at its lower exposed 55 end to said sliding frame to move it up and down, means for controlling said fluid pressure mechanism to move said sliding frame up and down, and a shaft carried by said sliding frame at its bottom provided with 60 projecting scarifier teeth.

3. A reversible scarifier for road rollers comprising a supporting frame adapted to be secured to a road roller and having facing groove-like trackways facing each other at the sides extending downwardly and rearwardly at an angle, a sliding frame having side bearing portions travelling in said trackways, fluid pressure mechanism secured to said supporting frame at the central top portion above said sliding frame and provided with a piston rod connected at its lower exposed end to said sliding frame to move it up and down, means for controlling said fluid pressure mechanism to move said sliding frame up and down, side rearwardly projecting flanges on said sliding frame at the bottom, a shaft mounted to turn in said flanges, a row of scarifier teeth projecting from said shaft, radiating arms secured to said shaft and movable over the inner faces of said flanges and an adjusting rod adapted to pass through said flanges and said arms to secure said shaft in position with the teeth projecting forwardly at an angle or rearwardly at an angle. 90

4. A scarifier for road rollers comprising a supporting frame adapted to be secured to a road roller and having parallel vertically extending trackways thereon, a sliding frame having side bearing portions traversing said trackways, scarifier teeth carried by said sliding frame, and cushioning means cooperating with said sliding frame and yieldingly resisting movements thereof from its working position. 95

5. A scarifier for road rollers comprising a supporting frame adapted to be secured to a road roller and having parallel vertically extending trackways thereon, a sliding frame having side bearing portions 100 traversing said trackways, scarifier teeth carried by said sliding frame, fluid pressure means cooperating with said sliding frame and adapted to raise and lower the latter and to yieldingly resist movements thereof 105 from its working position, and means for controlling said fluid pressure means. 110

6. A scarifier for road rollers comprising a supporting frame adapted to be secured to a road roller and having parallel vertically 115 extending trackways thereon, a sliding frame having side bearing portions traversing said trackways, scarifier teeth carried by said sliding frame, means for adjusting the angular relation of said teeth to the ground so that the scarifier is operable on forward or rearward movement of the roller, and cushioning means cooperating with said sliding frame and yieldingly resisting movements thereof from its working 120 position. 125

7. A scarifier for road rollers comprising a supporting frame adapted to be secured to a road roller and having parallel vertically extending trackways thereon, a slid- 130

ing frame having side bearing portions traversing said trackways, scarifier teeth carried by said sliding frame, means for adjusting the angular relation of said teeth to the ground so that the scarifier is operable on forward or rearward movement of the roller, fluid pressure means cooperating

with said sliding frame and adapted to raise and lower the latter and to yieldingly resist movements thereof from its working position.

In testimony whereof I affix my signature.

DAVID ERTER.
